UNITED STATES PATENT OFFICE.

JOHN H. WEDIG, OF GRANITE CITY, ILLINOIS.

HYPOTUBULE SYRINGE.

Application filed February 3, 1923. Serial No. 616,732.

To all whom it may concern:

Be it known that I, JOHN H. WEDIG, a citizen of the United States, residing at Granite City, in the county of Madison and State of Illinois, have invented certain new and useful Improvements in Hypotubule Syringes, of which the following is specification.

This invention relates to certain new and useful improvements in hypotubule syringes, the peculiarities of which will be hereinafter fully described and claimed.

The main object of my invention is to provide a tube with sealed ends and integral partition forming hermetically sealed contiguous and independent chambers containing respectively parts of a hypodermic syringe adapted to co-operate with the walls of one chamber, and a liquid located in another of said chambers for use in the syringe,—said syringe becoming operative only after the fracture of said chambers at predetermined points.

In the accompanying drawing on which like reference numerals indicate corresponding parts, Fig. 1, represents a central longitudinal section through a tubular device and contained parts exemplifying my invention; Fig. 2, a detached portion of one end that enclosed the cannula needle of Fig. 1; Fig. 3, a detached portion of the other end with its contained liquid, and a medicament capsule being emptied thereinto; Fig. 4, a detached intermediate portion of the tube; and Fig. 5, a detached main portion with contained parts constituting therewith an operative hypodermic syringe, showing the piston and plunger drawn outward and the stored liquid transferred thereinto.

The numeral 4 designates a tubular wall with the ends 5 and 6 thereof sealed, and an integral partition formed by constricting the tube walls at 7 till they meet and melt together to form a sealed integral partition intermediate of the ends as shown in Fig. 1. This integral partition may be otherwise formed than by constricting said walls.

A pair of separate independent contiguous and aligned chambers are thus formed,—one chamber 8 being of such size as to form a storage chamber for liquid deposited therein before sealing the end 6, thereby preventing any contamination or loss of volume of said liquid.

The other chamber 9 on the opposite side of the constricted portion 7, has contained

therein a fixed wall consisting of two parts,—a disc piece 10 and a conical piece 11, are cemented to the inner surface of the chamber 9 at a predetermined point, and provided with a recess 12 at their meeting faces which is traversed by a cannula needle 13 mounted in said partition by cementing its end in both of said pieces,—the recess 12 receiving the cement and forming an enlargement adhering to the needle so as to prevent its movement in said partition. The pointed end of the needle is thus sealed in the portion of the chamber 9 that is near the end 5 of Fig. 1, and the needle forms a communicating passage through the partition,—which partition is adapted to form the forward end of a syringe when fracture of the tube walls is effected at the plane 3—3.

On the opposite side of the partition from the needle point there is also located in said chamber 9 a piston 14, slideable therein and having a reduced end 15 on which is cemented the end of a tubular plunger 16 of lesser diameter than the chamber 9 and extending toward the closure 7. The plunger may be otherwise formed if desired. This chamber 9 is adapted to be fractured circumferentially at another plane 1—1 near the end of the plunger 16 so that it may be drawn out with the piston after the fracture of chamber 9 at the plane 1—1. Into this exposed chamber the liquid contained in the separate chamber 8 can be readily transferred after the fracture of the chamber 8 at the predetermined plane 2—2; the piston being then replaced in the open end of the chamber 9, and the needle exposed by fracture on the plane 3—3 before mentioned, the main portion of the tube walls, comprising the chamber 9 together with its contained parts assembled as in Fig. 5, constitutes an operative hypodermic syringe, the interior parts of which have been preserved in a sterile condition in the hermetically sealed chamber before mentioned.

The predetermined points of fracture are indicated by the scratched or partly cut circumferential lines on the outer surface of the tube at the indicated points 1, 2, and 3.

The chamber 8 may contain an aseptic liquid or a medicated liquid according to the use designed for the syringe. Such use and contents are indicated on a label 17 located on the interior of the chamber 9 adjacent to

the needle where it cannot be altered after sealing of the chamber. When the liquid in the storage chamber is desired to be medicated,—such medicament being kept in a solid or other separate condition till just before the use of the syringe,—a capsule 18 containing such additional or other medicament is located in the chamber 9 near the needle and is sealed. This capsule is thus 10 protected by the location in the hermetically sealed chamber but can be readily broken after separation of the tube at the plane 3—3 gives access to the capsule, which can then be broken and its contents emptied into the 15 liquid of the opened chamber 8, as indicated in Fig. 3. (If desired, the liquid may be introduced into the compression chamber by drawing it inward through the needle as the piston is pulled out). When located between the fixed partition and the drawn-out 20 plunger, the piston is pushed inward till the air, and a drop or two of the liquid, have been driven out through the cannula needle, and then the charged syringe is ready to be 25 discharged in the usual manner.

I claim:

1. A device of the character described comprising a tube with hermetically sealed ends, and divided by a partition forming 30 separate hermetically sealed chambers adapted to be fractured at predetermined points,—one chamber forming a storage chamber for a liquid sealed therein, and another chamber having a cannula needle mounted in a partition located near one end of the chamber adjacent to a piston and plunger slidably mounted therein and adapted to form a compression chamber to receive and eject the liquid deposited therein from 35 said storage chamber.

2. A device of the character described comprising a tube hermetically sealed at each end,—part of said tube constituting the walls of a syringe barrel and having a fixed wall with cannula needle and piston with 45 plunger located therein,—said tube having circumferentially cut lines near said fixed wall and the end of said plunger for effecting fracture at such points, substantially as described.

3. A device of the character described comprising a hermetically closed tube with integral partition forming a pair of hermetically sealed chambers alined with each other,—one chamber having a fixed wall partition,—a cannula needle mounted in and forming a passage through said partition, a piston and plunger also located in said chamber on the other side of said partition from said needle,—and the other chamber 55 forming a hermetically sealed storage chamber for a contained liquid,—said tube being adapted for fracture when desired at predetermined points.

4. A device of the character described comprising a tube adapted to be fractured transversely at a predetermined point, a fixed partition consisting of two pieces cemented at said predetermined point of fracture and consisting of a disc and a conical 70 piece forming an interior recess between the two, and a cannula needle centrally mounted in said fixed partition and traversing said recess and cemented in said partition,—the recess allowing an enlargement of cement 75 adhering to said needle and holding the needle against movement in the partition.

In testimony whereof I have affixed my signature.

JOHN H. WEDIG.
